UNITED STATES PATENT OFFICE.

ISIDOR POMERANTZ, OF ST. LOUIS, MISSOURI, ASSIGNOR TO FRED L. DICKEY, OF KANSAS CITY, MISSOURI.

FLASHING-BLOCK.

1,161,791.

Specification of Letters Patent. Patented Nov. 23, 1915.

Application filed January 23, 1913. Serial No. 743,799.

To all whom it may concern:

Be it known that I, ISIDOR POMERANTZ, a citizen of the United States, residing at 608 Frisco Building, St. Louis, in the State of Missouri, have invented certain new and useful Improvements in Flashing-Blocks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to flashing blocks, and more particularly to a device of that character adapted for use in the wall of a building adjacent a roof, in order that roof flashing may be applied and anchored there-to; the principal object of the invention being to provide a block to which the flashing may be secured and permanently anchored, irrespective of expansion and contraction of the flashing, and having means for carrying an auxiliary flashing, whereby water is deflected away from the point of anchorage of the main flashing. In accomplishing this object I have provided improved details of structure, the preferred forms of which are illustrated in the accompanying drawings, wherein—

Figure 1 is a sectional perspective of a building wall comprising a block constructed according to my invention, and showing the main roof and hood flashing, in combination with the block. Fig. 2 is an enlarged sectional perspective of the flashing block, here shown to be in the nature of an ordinary hollow tile, and more particularly illustrating the nailing block for the roof flashing. Fig. 3 is an enlarged detail perspective of the flashing block, showing the nailing strip partially removed. Fig. 4 is a sectional perspective of a modified form of block. Fig. 5 is a modified form or nailing strip. Fig. 6 is a detail perspective of a further modification of the flashing block.

Referring more in detail to the parts:—1 designates the wall of a building, and 3 the roof, which parts may be of any ordinary construction, except that the wall 1 comprises a flashing block 5 of tile or the like which faces inwardly a short distance above the roof. Each of the blocks 5 comprises a

lower groove 9, preferably dove-tail in construction, and adapted for containing a nailing strip 6; the outer face of which is flush with the outer face of the block, and an upper groove 8 which is also preferably dove-tail in shape and extends parallel with the lower groove 9 throughout the length of the block.

The roof flashing 4, which may be of any ordinary type, is extended upwardly along the wall at the edge of the roof and nailed or otherwise secured to the nailing strip 6, so that its upper edge terminates below the upper block groove 8. Projected into the upper groove 8 is a hood flashing 7, the lower edge of which overhangs the upper edge of the roof flashing 4, while its upper edge is held in the groove 8 by cement, or the like, which is filled into the groove after the flashing has been placed.

In Fig. 4 I have shown a modification of the above structure, wherein the nailing strip 15 is set into the wall 14 and provided with upper and lower recesses 18—19, into which plaster or cement that anchors the strip in place is projected in order to form keys for holding the strip in place. With this construction, the roof flashing 20 is nailed to the outer face of the strip and the hood flashing 16 is secured to the upper edge of the strip, so that it is secured in the plaster within the wall and overhangs the upper edge of the roof flashing.

In the modification shown in Fig. 5, 22 designates the block which is seated in the wall and has upper and lower recesses 25—26 for receiving the cement or plaster as described with reference to Fig. 4. The block 22 has a dove-tail groove 27 in its outer face within which a nailing strip 23 is removably mounted. With this construction the hood flashing is set into the wall at the upper edge of the block so that it overhangs the nailing strip 23, and the roof flashing (not shown) is secured to the nailing strip after the block has been set and before the hood flashing is bent down to its functional position.

In the modification shown in Fig. 6, the block 30 is provided with a longitudinal groove in its upper face, into which the hood flashing may be projected in order to securely anchor the same in place; the block having a longitudinal dove-tail 32, like

those heretofore described, and adapted for containing a nailing strip 33 of the character described.

In using my invention, the flashing 5 blocks of tile or the like are set into the wall of a building, while the latter is being erected, and slightly above the roof position.

When the roof is in place, the roof flashing 10 is applied thereto and the edges of the flashing turned upwardly along the wall and nailed to the nailing strip. After the roof flashing has been secured to the nailing strip of the block, the upper edge of 15 the hood flashing is projected into the anchoring groove and a key of cement filled into the groove to hold the roof flashing thereto; the hood flashing being of sufficient width to overhang the upper edge 20 of the roof flashing, so that rain or melting snow passing down the side of the wall will be deflected over the upper edge of the

roof flashing instead of passing back of the flashing to rot the flashing and leak into the building.

25

Having thus described my invention, what I claim as new therein, and desire to secure by Letters-Patent, is:—

A noggin block formed in a single piece with parallel upper and lower grooves in 30 one side face thereof, a main flashing bearing flat upon said face, means for securing the main flashing to the lower grooved portion of the block, a counter flashing bearing upon the main flashing, and means 35 for anchoring the upper edge portion of the counter flashing within the upper groove.

In testimony whereof I affix my signature in presence of two witnesses.

ISIDOR POMERANTZ.
